UNITED STATES PATENT OFFICE.

HUGH ROSS TOOKER AND HARRY LEIGH TOOKER, OF SANTA MARIA, CALIFORNIA.

PEN OR PENCIL HOLDER.

1,147,198.

Specification of Letters Patent.

Patented July 20, 1915.

Application filed August 5, 1914. Serial No. 855,189.

To all whom it may concern:

Be it known that we, HUGH ROSS TOOKER and HARRY LEIGH TOOKER, citizens of the United States, residing at Santa Maria, in the county of Santa Barbara and State of California, have invented a new and useful Pen or Pencil Holder, of which the following is a specification.

This invention has reference to pen or pencil clips or holders, and its object is to provide a simple form of clip which will firmly hold the pen or pencil in a pocket of a garment, but from which it may be removed with great facility.

15 In accordance with the present invention there is provided a main or body portion having a short barrel for embracing the pen or pencil, and in the case of a pen, particularly a fountain pen, the body portion may, 20 if desired, be permanently secured to the barrel of the fountain pen, although ordinarily the barrel may be made to so tightly grasp the body of the fountain pen as to remain thereon without liability of displacement under ordinary conditions of use.

Carried by the body portion of the clip is another member having spurs, or spur-like parts movable through the body member or to either or both sides of said member, in 30 such manner that the latter serves as a shield for the spurs, and such spurs are so related to the body member that by a proper manipulation of the part carrying the spurs, said spurs will enter the cloth of the pocket into 35 which the pen or pencil is introduced, thereby effectively anchoring the clip to the pocket against any liability of displacement so long as the spurs remain in the cloth. However, by pressure suitably applied to the spur-carrying member these spurs are withdrawn 40 from the cloth and their points are sheathed in or shielded by the body member in a manner effectively protecting the cloth from engagement by the spurs, whereupon the pen or pencil with the clip attached is readily withdrawn from the pocket.

In the more specific structure of the present invention there is a body member carrying an embracing portion for the pen or 50 pencil and a spur-carrying member in hinged or pivoted relation to the body member, so that by pressure properly applied to the pivoted member the spurs are withdrawn from the active position so as to be sheathed in or 55 shielded by the body member, while the piv-

oted member has a normal tendency toward the active position.

In the broader aspects of the invention different mechanism means from the particular arrangements herein disclosed may be 60 utilized and some of these various mechanical means are shown and described and specifically claimed in other applications filed by us on even date herewith under Serial Numbers 855,190 and 855,191, but in the said 65 other applications the broader aspects of the invention are not claimed, since the broader or more comprehensive claims based upon the broader principles of the invention are made in this case.

70 The invention will be best understood from a consideration of the following detailed description taken in connection with the accompanying drawings forming a part of this specification, but it is to be understood that the invention is susceptible of a great variety of embodiments in its broader aspects, some of which embodiments are shown in the aforesaid applications, wherefore the invention is not limited to any strict 75 conformity with the showing of the drawings in either this or the other named applications, since the structures herein and therein shown may be changed and modified, or the invention may be embodied in other 80 structures so long as such structures mark no material departure from the salient features of the invention as expressed in the appended claims.

85 In the drawings: Figure 1 is a perspective view of one form of pen or pencil clip embodying the invention. Fig. 2 is a longitudinal section of the clip of Fig. 1 applied to a pen or pencil, and in position in a pocket. Fig. 3 is a view similar to Fig. 2 but showing the position of the parts when manipulated to withdraw the spurs for the removal of the pen or pencil, together with the clip from the pocket. Fig. 4 is an edge view of 90 another form of pen or pencil clip applied to a pencil and in position in a pocket, the material of the latter being shown in longitudinal section. Fig. 5 is a longitudinal section of the structure of Fig. 4 but illustrating the position of the parts when it is 95 desired to withdraw the pen or pencil from the pocket. Fig. 6 is a side view of a structure similar to but varying somewhat in details from that of Figs. 4 and 5. Fig. 7 is a 100 longitudinal section of the structure of Fig. 110

6 with the parts in position causing the retraction of the spurs. Fig. 8 is a side view of still another form of the invention. Fig. 9 is a longitudinal section of the structure of Fig. 8, with the parts in the position causing the retraction of the spurs. Fig. 10 is a section on the line 10—10 of Fig. 8. Fig. 11 is a section on the line 11—11 of Fig. 8. Fig. 12 is a front elevation of still another form of the invention. Fig. 13 is a longitudinal section of the structure of Fig. 12. Fig. 14 is a side view of a modification of the structure of Figs. 12 and 13.

While the invention is adapted for use 15 with either a pen or pencil, it is particularly useful in connection with a fountain pen, and for the sake of simplicity of description the article to which the clip is applied will hereinafter be considered as a fountain pen 20 without, however, limiting the use of the clip to such a particular article.

As it is customary to construct pen clips of sheet metal, it will be assumed that the clip of the present invention is also formed 25 in whole or in part of sheet metal without, however, confining its construction to such particular material.

In the structure of Figs. 1, 2 and 3 there is provided an elongated strip 1 formed near 30 one end with curved portions 2 extending laterally from the strip 1 and approaching at their outer ends, so that the strips together form a barrel through which the body of a pen 3 may be inserted, it being 35 assumed for purposes of description that the pen 3 is a fountain pen. The barrel 2, being in the particular instance shown formed of two suitably curved members, is usually 40 made of a diameter to snugly embrace the body of the pen, so that under ordinary conditions of use the clip will hold its position on the pen, the latter being employed in the act of writing without removing the clip from the body of the pen. Sometimes 45 it is desirable to make the clip permanently fast to the body of the pen, and this may be done in any of the usual ways, and it will be understood that the clip is either applicable to or removable from the pen body 50 at will or may be permanently attached to the pen body, without further showing or description. That end of the body strip 1 remote from the end near which the barrel 2 is formed is bent at approximately right 55 angles and then rebent upon itself to form an end guard 4, the return portion of the end guard 4 being provided with a slot 5 for a purpose which will presently appear. There is also provided another elongated 60 strip 6 having laterally extended ears 7 formed thereon near the middle, these ears being bent into parallelism and spaced apart so as to embrace the strip 1 adjacent to the barrel 2 and between the latter and the 65 guard end 4. Formed on or fast to the strip

1 so as to traverse the ears 7 are pintles 8, the arrangement being such that the manipulating member 6 may be rocked upon the pintles 8 as upon a hinge or pivot. The member 6 is slightly curved longitudinally 70 and near the end corresponding to the barrel 2 may be cross hatched or milled, as shown at 9, to form a finger-hold. Under ordinary conditions of use the end of the member 6 having the milling 9 is extended 75 beyond the latter, as shown at 10, and is so curved that the end 10 bears against the corresponding end of the body member 1, while the other end of the member 6 is in engagement with the body member 1 adjacent to the end 4. Pressure applied to the milled portion 9 causes a yielding of the spring end 10 so that the manipulating member 6 will rock upon the pintles 8 as upon a pivot, thus causing the other end, indicated 80 at 11, to move away from the corresponding portion of the body member 1, such end 11 being held normally in contact with such portion of the body member by the action of the spring end 10. The end 11 terminates 85 in a tongue 12 entering the slot 5, so that movements of the end 11 away from the corresponding end of the body member 1 are limited by the length of the slot 5. Adjacent to the end 4 the body member is traversed by passages 13 and carried by the end 11 of the member 6 are corresponding spurs 14, so located as to move through the body member by way of the passages 13, and these spurs are inclined or curved from 90 their point of emergence from the end 11 of the member 6 toward the barrel 2.

In Figs. 2 and 3 are shown the back wall 15 and front wall 16 of a pocket, and this pocket may be taken as a vest or coat pocket, 105 since it is quite customary to carry fountain pens in such pockets. Let it be assumed that it is desirable to insert a pen 3 in the pocket, pressure is applied to the milled portion 9, thus tending to flatten out the 110 corresponding curved end of the member 6. This causes a rocking of the member upon the pintles 8 and a corresponding movement of the end 11 away from the body member 1, the movement being sufficient to cause the 115 withdrawal of the spurs 14 until their points are sheathed within the passages 13, and the length of the slot 5 may be such that at this point further movement of the end 11 away from the body member 1 is 120 arrested by the engagement with the tongue 12 with the outer wall of the slot 5. With the parts in such position the pen is readily introduced into the pocket with the corresponding end of the body member 1 exterior to the front portion 16 of the pocket. Now, on releasing the pressure upon the member 6 at the milled portion 9, the elasticity of the compressed portion causes it 125 to return to its normal position, which re- 130

turn at the same time causes the spurs 14 to project through the passages 13, and enter the cloth of the front 16 of the pocket, and the body member 1 is sufficiently close to the 5 body of the pen 3 to elastically clamp the pen to the pocket. The pen cannot be removed while the parts are in the position just described, because of the engagement of the spurs in the cloth of the front portion 10 of the pocket. If, however, it be desirable to remove the pen with the clip from the pocket, pressure is again applied to the milled portion 9, when the parts will assume the position shown in Fig. 3, that is, with 15 the spurs withdrawn from the pocket front section 16. Since the cloth is now entirely protected or shielded by the body member from engagement with the spurs and the latter are prevented from catching any loose 20 or projecting threads of the cloth, the pen together with the clip is readily removed from the pocket for use and may be reinserted and secured to the pocket in the same ready manner.

25 In Figs. 4 and 5 there is shown a somewhat simpler construction in that there is a body member 1^a having a barrel 2^a which may be made separately from and secured to one end of the strip 1^a in any suitable 30 manner, as by rivets 17, although, of course, the barrel 2^a may be otherwise formed. That end of the body member 1^a carrying the barrel 2^a has ears 7^a formed thereon, and pivoted between these ears is a strip 35 6^a carrying at one end beyond the barrel 2^a a spring 10^a while at the other end this strip is provided with spurs 14^a as in the form of Fig. 1. The strip 6^a is formed at the end remote from the spring 10^a with a 40 tongue 12^a, while the corresponding end of the body member is returned upon itself in substantially ring form as shown at 4^a, and through which ring there is a slot 5^a for the passage of the tongue 12^a. The body 45 member 1^a has passages 13^a for the spurs 14^a. The pen 3 is held in the barrel 2^a as in the first described form, but instead of the member 6^a being held in the active position by bearing against the body member 50 1^a, the spring 10^a bears directly against the pen 3. In Fig. 4 the device is shown in position in a pocket composed of the back member 15 and front member 16, and in Fig. 5 the parts are shown in the position assumed 55 when pressure is applied at that end of the strip 6^a provided with the spring 10^a. The operation of the structure is the same as already described with reference to Figs. 1, 2 and 3. In the structure of Fig. 1 but two 60 spurs are shown, while in the structure of Fig. 4 three spurs are shown. It will be understood, however, that the number of spurs may vary from one spur to as many as desired, although usually two or three 65 spurs are sufficient.

In Figs. 6 and 7 there is shown a barrel member 2^b formed with a longitudinal extension 18 from the portion of the barrel remote from the split part thereof and secured to the barrel member is a block 19 as 70 by rivets 20 or otherwise. The block 19 is formed with spaced ears 21 receiving pintles 22 on opposite sides of a strip 6^b having at one end a spring 10^b engaging the extension 18, while the other end carries 75 spurs 14^b and is provided with a tongue 12^b entering through a slot 5^b into a ring-shaped extremity 4^b on the end of a body member 1^b secured in the block 19 which may be recessed for the purpose, and one of the rivets 80 20 may be utilized for the purpose of securing the body member 1^b to the block 19. In the preceding showings of the spur-carrying member 6 or 6^a the spurs are shown as 85 separately formed and appropriately secured to the carrying strip by riveting or otherwise. In the structure of Figs. 6 and 7 the spurs are struck up from the material of the spur member 6^b instead of being separately formed therefrom, and it will be understood that the same procedure may be followed with respect to the other forms of the invention. The body member 1^b has 90 passages 13^b for the spurs. The operation of the structures of Figs. 6 and 7 is the 95 same as that of Figs. 4 and 5, except that the spring 10^b engages the extension 18 instead of being brought into engagement with the body of the pen 3.

In the structure of Figs. 8 to 11 a barrel 2^c is formed near one end of a body member 1^c which may be a strip of greater length than in the structure of Fig. 1. Adjacent to one end of the barrel 2^c the body member 1^c is formed into a curved or bulged section 22^c projecting from that face of the body member remote from the barrel 2^c. The body member is continued from the part 22^c for an appropriate distance in line with that portion of the body member carrying the barrel 2^c and at an appropriate point is provided with passages 13^c for spurs 14^c on the corresponding end of a spur-carrying strip 6^c, the other end of this strip being made fast to the corresponding end of the body member 1^c by rivets 23 or otherwise. The spurs 14^c are struck up from the material of the spur carrier 6^c as in Figs. 6 and 7, or they may be separately formed and secured thereto as in Figs. 1 to 5. The body member beyond the perforations 13^c is bent away from the barrel side of the body member at an inclination as shown at 24, and then is returned toward the curved or bulged portion 22^c until overhanging the latter, as indicated at 25, this return portion being bowed away from the main portion of the body member. The spur end of the spur carrier 6^c enters between the bowed or bulged portion 22^c and the corresponding 110 115 120 125 130

end of the return part 25 of the body member. The spur carrier has a normal tendency to project the spurs through the perforations 13^c and this tendency may be assisted by an elastic tendency of the return portion 25, the end of which may normally contact with the spur carrier adjacent to the bulged portion 22^a. If, now, pressure be applied to the spur carrier between the bulge 22^a and the riveted end of the spur carrier, as, for instance, at the point indicated at the arrow 26, the spur carrier will rock on the bulged portion 22^a in a direction to withdraw the spurs 14^c from projection through the perforations 13^c so as to withdraw from the cloth into which they may enter. With a pen introduced through the barrel 2^c the operation of the device of Figs. 8 to 11 is similar to that of the other figures. The presence of the barrel 2^c and bulge 22^a sufficiently stiffens the body portion 1^c of the structures of Fig. 8 and associated figures to permit the movements described without undue bending of the body portion.

In Figs. 12 and 13 there is a body portion 1^a which may be made of a strip of heavier metal than before, and formed on or attached to this strip is a barrel 2^a. That end of the body member 1^a remote from the barrel 2^a is outturned, as indicated at 24^a, and at a point near its outturned end the body portion is formed with a passage 13^a large enough to receive a block 27 carrying spurs 14^a on one face, and a knob or headed pin 28 on the other face. Adjacent to the passage 13^a between the same and the angle extension 24^a and on the face remote from that on which the barrel 2^a is located, there is a laterally elongated ridge 29. The spur carrier in the structure of Figs. 12 and 13 is in the form of a bowed strip 6^a of spring metal which adjacent to the barrel 2^a is traversed by a pin 30 having a head 31 at its outer end, while the strip 6^a is provided with an elongated slot 32 through which the headed pin 30 passes. The strip 6^a is long enough to extend beyond the block 27 and is traversed by the headed pin 28 and beyond the pin is formed with a bead 33 fitted to the ridge 29.

In Fig. 14 the structure is the same as in Figs. 12 and 13, except that there is a ridge 29^a on that side of the opening 13^a as the barrel 2^a and the strip 6^a has a corresponding bead 33^a which, together with the ridge 29^a forms a hinge upon which the strip 6^a turns, with the result that the block 27 is moved to withdraw the spurs 14^a as before.

In all the forms of the invention illustrated in the drawings, the spurs are normally projected through that portion of the device which contacts with the cloth of the pocket in which the pen is to be held, and these spurs are withdrawn by pressure applied in a direction to cause their movement in the

reverse direction to their normal movement. Furthermore, the body member through which they project constitutes a shield or guard for the spurs, preventing them from catching in the cloth of the pocket when the device is inserted or withdrawn from the pocket. The arrangement also is such as to be capable of manipulation with one hand, so that the device is inserted into the pocket or withdrawn therefrom with the greatest facility, but at the same time when a pen provided with the clip of the present invention is introduced into the pocket, it is locked therein so effectively that it cannot be withdrawn accidentally by any force short of one destructive to the device, or to the pocket. The spur carrier has a normal tendency to project the spurs and hence the device automatically locks in position as soon as released.

In the present invention the movement of the spurs is brought about by a hinge action, while in structures such as shown in the aforesaid applications the movements of the spurs are brought about by other than hinge actions, between a body member and an elongated spur carrier lying along the body member, and of a length approximating or longer than that of the body member. Moreover, the only guard for the spurs is the body member through which they normally project, and which when the structure is to be inserted in or removed from a pocket acts as a guard or shield, and these spur members are readily withdrawn by the pressure between the thumb and one finger of one hand engaging the pen and a part acting to cause the retreat of the active ends of the spurs away from the cloth-engaging face of the spur-guarding part of the structure.

What is claimed is:—

1. A holding clip for pens and the like comprising an elongated body member having a barrel near one end for attachment of the body member to the pen and with normally projecting spurs spaced away from the barrel in the direction of the length of said body member to be in coactive relation with the attached pen, and means for causing the withdrawal of the spurs from projecting relation to that face of the body of the clip toward the pen, whereby on the insertion of the pen in a pocket with the body member exterior to the pocket said body member clamps the cloth of the pocket against the pen and the spurs project through the cloth toward the pen.

2. A holding clip for pens and the like comprising an elongated body member with means for attachment of the body member to a pen, and spur-like means in projecting relation to the body member on the same side thereof as the pen, said means of attachment of the body member to the pen and said spur-like means being spaced apart lengthwise of

the body member to bring the spurs into operative relation to the pen at a distance from the attaching means for the pen, whereby the spurs will enter the cloth of a pocket when such cloth is located between the pen and the body member, and means for causing the withdrawal of the spurs from the cloth and the sheathing of said spurs with respect to the cloth when it is desired to introduce the pen into the pocket or withdraw it therefrom.

3. A clip for pens and the like comprising an elongated body member having means for the attachment of the body member to a pen, and spurs spaced away from said means in the direction of the length of the body member and normally projecting toward the pen when the body member is attached thereto, whereby the spurs enter the cloth of a pocket next to the pen when the pen is introduced thereinto, and said clip having guarding means for the spurs in which the points of the latter are housed out of the path of the cloth when the pen and clip are being applied to or removed from the pocket.

4. A clip for pens and the like comprising an elongated body member, means near one end of the body member for securing it to the pen in position to provide for the insertion of the pen into a pocket with the outer portion of the pocket between the body member and the pen, spurs carried by the body member near the other end thereof in position to enter the cloth of the pocket when between the body member and the pen, and guarding or shielding means for the spurs through which the latter project when in operative position, said spurs and guarding means having relative movements to cause the retraction of the spurs from the cloth and the holding of said spurs out of engaging relation with the cloth when the parts are being introduced into or removed from the pocket.

5. A holding clip for pens and the like having means for the attachment of the clip to the pen and provided with spurs in spaced relation to said means of attachment and in normally active projected position, and a shield for the spurs, said clip being also provided with manipulating means for causing a relative movement of the spurs and shield to withdraw the spurs into the shield, and said manipulating means constituting a handle portion at the end of the clip remote from the means of attachment to the pen, for the insertion of the pen with the clip applied thereto into a pocket and the withdrawal of said pen and clip from the pocket with the spurs in the retracted or inactive position.

6. A clip for pens and the like comprising a body member having a pen receiving barrel near one end and passages through

the body member near the other end, and a rockable carrying member on the body member provided with spurs having their pointed ends normally projecting through the passages in the body member, the spurs projecting beyond that face of the body member carrying the pen receiving barrel and the rockable member having a range of movement to cause the withdrawal of the pointed ends of the spurs from projecting relation to said face of the body member, whereby the body member constitutes a shield or housing for said pointed ends of the spurs when the latter are in the retracted position.

7. A clip for pens and the like comprising an elongated body member having means near one end for the attachment of the body member to the barrel of a pen, and said body member having passages therethrough near the end remote from the attaching means to the pen, and a rockable member on the body member provided with spurs normally projecting through the passages in the body member with their points in projecting relation to that face of the body member toward the pen, and said rockable member being yieldable to pressure to withdraw the spurs from projecting relation with respect to the body member.

8. A clip for pens and the like, comprising an elongated body member with means adjacent to one end for attachment to the body of a pen and near the other end provided with perforations and with an outstanding guard, and an elongated spur carrier pivotally connected to the body member and at one end entering and guided by the guard and adjacent said end having spurs adapted to the passages in the body member, said spur carrier having a normal constraint to cause the projection of the spurs through the passages in the body member.

9. A clip for pens and the like comprising an elongated body member having means for attachment to the body of a pen and at one end formed with an outstanding guard on the side remote from the pen body when attached, and a spur carrier pivotally connected to the body member with one end in guided relation to the guard and adjacent thereto provided with spurs, the body member having perforations therethrough for the spurs and there constituting a shield for the spurs when retracted, the spur carrier having a normal constraint to move the spurs through the body member into projecting relation thereto.

10. A clip for pens and the like comprising an elongated body member formed with a pen receiving barrel and at one end with an outstanding guard and an elongated spur carrier pivotally connected to the body member with spurs near one end and at said end entering the guard on the body mem-

ber, and with spring means at the other end of the spur carrier for constraining the carrier to move the spurs into projecting relation to the body member on the side thereof 5 toward the pen when attached thereto, the body member being provided with passages for the spurs and constituting a shield or sheath for the spurs when in the retracted position.

10 11. A holding clip for pens and the like comprising an elongated member having means near one end for attachment to the pen and near the other end provided with spurs normally projecting beyond the pen 15 side of the clip, and means for causing the withdrawal of the spurs from such projecting relation to the pen side of the clip.

12. A holding clip for pens and the like comprising an elongated and relatively flat 20 body member having means on one side near one end for attachment to the barrel of a

pen, and a member provided with spurs and mounted on that face of the body member remote from the pen holding means and having a normal tendency to carry the spurs so that the free ends thereof are in projecting relation to the pen carrying face of the body member near the end remote from the means for attachment to the body member to the barrel of a pen, said second member 25 being yieldable to pressure to withdraw the spurs from projecting relation to the pen carrying face of the body member.

In testimony, that we claim the foregoing as our own, we have hereto affixed our signatures in the presence of two witnesses.
